UNITED STATES PATENT OFFICE.

WILLIAM C. NICHOLSON, OF OAK PARK, ILLINOIS.

ROTATING ENGINE AND OPERATING CONNECTIONS THEREFOR.

Application filed July 7, 1919. Serial No. 309,103.

To all whom it may concern:

Be it known that I, WILLIAM C. NICHOLSON, a citizen of the United States, and a resident of the village of Oak Park, in the 5 county of Cook and State of Illinois, have invented certain new and useful Improvements in a Rotating Engine and Operating Connections Therefor; and I do hereby declare that the following is a full, clear, and 10 exact description of the same, reference being had to the accompanying drawings, and to the numerals of reference marked thereon, which form a part of this specification.

In engines of this type the cylinder is 15 equivalent to one shaft of the gimbal-joint and rotates with the piston. An idle shaft journalled in fixed bearings to rotate at an angle to the axis of rotation of the cylinder is equivalent to the other shaft of the gimbal-joint.

20 An abutment rigidly attached to the cylinder and rotating therewith extends from one wall of the latter to the piston and contacts therewith along a line parallel to the 25 axis of oscillation of the piston relatively to the cylinder.

If the cylinder rotates the chambers 30 formed by the piston on either side of the abutment alternately increase and decrease in volume owing to the double oscillation of the piston first relatively to the cylinder and second relatively to the idle shaft. By suitably introducing fluid under pressure on opposite sides of the abutment alternately rotation of the cylinder is produced.

35 It is an object therefore, of my invention to provide means for supporting the rotating cylinders at both ends.

A further object is to provide means 40 whereby a single valve controls a plurality of cylinders.

It is also an object of my invention to provide a valve in which the use of reciprocating or oscillating parts are avoided.

45 Furthermore an object of my invention is to provide means for readily reversing the engine and at the same time enabling the fluid admission to be cut off at the desired point when the engine is running in either 50 direction.

It is an object of this invention to provide an engine adapted for general power purposes and because of its exceedingly compact construction and the high power

55 efficiency developed is particularly adapted for use in the operation of portable power

driven devices, such, for example, as have heretofore been operated by compressed air, in other words, pneumatic tools.

It is a further object of the invention to 60 provide a construction adapted for high speed and minimum vibration and utilizing the momentum of the entire engine effectively when in operation.

It is also an object of the invention to 65 provide a construction adapted to develop high power efficiency but occupying very small space and directly connected with the element to be driven through the medium of a casing which affords the engine frame and 70 likewise encloses the rotative parts, thus protecting the engine from injury and dirt and affording a protection from contact with the rotating elements of the device, and so constructed as to permit the quick 75 removal of the engine proper and substitution of a like engine.

The invention in a preferred form is 80 shown embodied as a pressure operated portable steam or pneumatic tool of the rotative type, such, for example, as is used for drilling, boring and polishing and is more fully hereafter described.

On the drawings:

Figure 1 is a central longitudinal section 85 partly in elevation of a machine embodying my invention.

Figure 2 is an enlarged detail view partly in section of the tool holder and thrust shaft of the machine.

Figure 3 is an enlarged central section 90 through the connection between the source of fluid pressure and the valve chest.

Figure 4 is an enlarged longitudinal vertical section through the engine detached 95 from its casing or frame.

Figure 5 is a section on the line 5-5 of Figure 4.

Figure 6 is a section on the line 6-6 of Figure 1, with the bottom of the gear case 100 removed.

Figure 7 is a bottom plan view.

Figure 8 is a top plan view of the machine.

Figure 9 is a view partly in section with 105 half of a cylinder removed and the pistons and some of the related parts in elevation.

Figure 10 is a plan view of the piston with all of the parts connected thereto removed.

Figure 11 is a section on the line 11-11 of 110 Figure 4, with the piston removed.

Figure 12 is an enlarged section taken on line 12—12 of Figure 9.

Figure 13 is an enlarged horizontal central section of a modified form of valve construction embodying means for reversing and varying the cut-off.

Figure 14 is a section on the line 14—14 of Figure 13.

Figure 15 is a section on the line 15—15 of Figure 13.

Figure 16 is a section on the line 16—16 of Figure 13.

As shown in the drawings:

The engine comprises duplicate rotative 15 globular or spherical members termed cylinders and rigidly connected together by means of a valve mechanism affording the inlet and the exhaust means for each cylinder. Said engine rotates as a whole on a 20 common axis of said cylinders upon suitable axially aligned bearings at each end of the device, and also in a central bearing afforded by the valve casing. The tool holder is supported parallel the axis of rotation of 25 the engine and in alignment with a threaded thrust bar or shaft whereby thrusting pressure may be varied on the tool as desired, and a reduction gearing is provided between the engine or motor and the tool holder to 30 afford a positive drive. All of the operating parts of the mechanism as a whole are enclosed within the frame casing, which serves to hold the engine and the parts driven thereby in an unvarying relation.

35 The frame casing as shown is preferably constructed of cast metal and affords two chambers, one a relatively large longitudinally disposed chamber to receive the engine through which the thrust shaft extends, and 40 a lower chamber affording a gear casing. Said casing as shown is constructed in three parts abutting each other and rigidly secured together transversely of the casing by means of suitable cap screws or otherwise, 45 and comprise a central casing section 1, provided near its lower end with a transverse partition 2, to receive the lower end of the lower cylinder of the engine. Said central section of the casing extends upwardly to 50 approximately the plane passing through the center of the upper cylinder and there is flanged outwardly as indicated at 3, to receive the corresponding flange 4, of the upper frame casing member 5, as shown in 55 Figure 1, into which the upper half of the upper cylinder of the engine projects.

Secured to afford the lower end of the frame casing is a peripherally flanged head, the flanges of which engage with the downwardly directed flanged edges of the central casing by means of cap screws, and together therewith forms a lower gear chamber. Rigidly secured substantially at the 60 axis of said frame casing in the upper casing section 5, is an inwardly extending stud 65

shaft 7. Means for engaging said shaft in said casing may, of course, vary with the size of the power unit. As shown, the shaft 7, is of a reduced diameter at the point where it passes through the wall of said upper casing and is threaded at its outer end to receive a clamping nut in a familiar manner to draw the shoulder afforded by said reduction in diameter of the shaft firmly against the inner wall of said casing section. In a similar manner, a stud shaft 8, is rigidly secured in the cap or end casing member 6, affording the bottom of the gear case and projects upwardly to afford a lower end bearing for the engine.

80 The engine is journaled on said shafts 7 and 8, as shown in Figures 1 and 4, and in the construction illustrated in the drawings, in which two power cylinders of spherical form are shown, each of the cylinders is divided transversely in a plane passing through their centers and each consists as shown of the lower semi-spherical sections 9 and 11, the complementary upper sections therefor are the cylinder sections 90 10 and 12, affording the respective pressure chambers for said power unit. It is to be noted that for convenience of construction, the cylinder sections 9 and 12 are duplicate, and the cylinder sections 10 and 11 are also 95 duplicate in all respects. Said cylinder sections of each cylinder are fitted together so that the section subjected to the highest temperature fits within the other section at the joint to afford a joint that is not endangered by expansion and the joint is further strengthened by a union ring 23, which firmly engages a bead or rim on one cylinder section and threaded onto the other.

100 The lower end of the lower cylinder and the upper end of the upper cylinder are each provided with a flange integral with said respective lower and upper cylinder sections 9 and 12, and indicated by 13, which project outwardly therefrom concentric with the axis and afford oppositely directed hubs and through which a cylindric bore opens into each cylinder. The hub on the lower cylinder fits into a complementary aperture 110 afforded in the partition 2, and suitable packing shown in Figure 1, is provided at the bearing afforded thereby to prevent any water of condensation finding its way into the gear casing in the event that steam is 115 used.

120 Journaled on the lower stud shaft 8, is a sleeve 14, provided at its upper end with a cylindric collar 15, which fits closely in and is rigidly secured to said lower hub 13, and integrally connected with which is a yoke hereinafter more fully described with reference to the description of the piston and operation. Fitted within the flange of the collar 15, is one of the members 16, of a 125 130

ball or roller bearing, as preferred, the other bearing member 17, of which is rigidly secured on the stub shaft 8, which has on its inner end an obliquely directed integral bracket or stationary crank shaft 18, (which will be described in connection with the piston and its operation). In a similar manner, a yoke bearing collar 15, is fitted within and rigidly secured to the hub 13, of the upper cylinder and rigidly secured thereto and therein is a sleeve 17, affording one member of a ball or roller bearing 16, the other member of which 17, is rigidly secured on the inwardly directed end of the stub shaft 7, balls or rollers in each instance being interposed between said members. A bracket which acts as a stationary crank shaft 18, similar to that before described is integrally secured thereto.

5 The cylinders are rigidly connected with each other through the medium of internal abutments 20 and 20^a, and a cylindrical valve block 21, rigidly uniting said abutments. The latter project into the respective cylinders to near the center thereof and are of duplicate construction, each having inclined side walls arranged approximately at right angles with each other and affording an apex slightly concave for its entire length having a packing recess therein, in which is a suitable packing extending across the cylinder on a cord approximating the diameter of the cylinder. The apices of the 10 respective abutments in said cylinders are also directed at a right angle with each other, as shown in Figure 4. The valve block 21, is axially disposed between and rigidly connects said abutments and is of a length to extend into seats complementary with the ends of said valve block in said abutments, as shown in Figure 5. If preferred the adjacent abutments, the containing half cylinders and the valve block may be constructed integrally. Said valve block 15 is provided with four ports 21^a and 21^b, arranged parallel the axis thereof and registering with corresponding ports opening through the sides of said abutments, two of the ports, as shown in Figures 4, 5 and 11, opening one through each side of each abutment, through the oppositely inclined walls thereof, said ports increasing inwardly in transverse area to reduce resistance of the flow of the pressure fluid, cap screws 19, extending through the dead ends of said ports in the valve block 21, into the respective abutments, thus affording a very rigid connection between the abutments and in axial alignment with the stub shaft before described. Said abutments are shaped to fit complementally into the side walls of said inner cylinder sections and are rigidly connected therewith.

15 The ports from said valve blocks open 155 therefrom through the periphery of the

blocks as shown in Figure 5. Between the adjacent ends of said cylinders is a stationary valve chest casing parted centrally through the axis thereof, and the two sections secured together by cap screws 22, and is provided on the inlet side 24, within inlet pipe 25, and an inlet pressure chamber 26, and on the opposite side with an exhaust chamber 29, opening therefrom and an exhaust pipe 28. The inner walls of the 70 valve casing for that portion thereof contacting the valve block, are of unequal length owing to the fact that the inlet chamber is shorter on the periphery of the valve block than the exhaust chamber. That is to say, the web of said valve casing bearing against the periphery of the valve block is relatively long between the positions of closing the inlet port and the opening of 75 said port at exhaust position to obtain the value of the steam or pressure expansively, while the web between the termination of the exhaust chamber and the beginning of the inlet port is relatively short to permit substantially immediate inlet of pressure at 80 the end of the exhaust. It will be noted owing to the right angular arrangement of the ports and the abutments through which the ports open into the cylinders, the inlet impulses and exhaust from the respective 85 cylinders will be alternately and in sequence, and that the inlet to each cylinder takes place before the cut-off for the other, thus avoiding possibility of dead center. As 90 shown, a sleeve 30, integral with the central frame casing provides an aperture through which the pressure inlet pipe 31, extends, and closely fits and is secured. This, of course, and as shown in Figure 3, 95 registers with the end of the inlet pipe 25, which is provided at its outer end with a flange or hub 32, fitting over the inwardly extending end of the inlet pressure pipe 31, and between which is provided a relatively 100 large packing chamber containing a packing which may vary of course, with the character of the pressure fluid, but conveniently may be a hydraulic packing, as shown at 33 wherein the pressure fluid acts to press the valve casing inwardly against the valve block thereby always insuring a tight joint with the valve block on the pressure side inasmuch as the pressure in the exhaust 105 side of the valve chamber is but slightly 110 above atmospheric pressure. It will be observed that the valve casing affords a central floating bearing for the valve blocks whereby the two cylinders are rigidly connected to rotate together, and which cannot be affected by any stresses applied to 115 the inlet pipe 31, which also acts as an operating handle.

120 A piston 34 and 34^a, is provided respectively in each of the cylinders and mounted to oscillate therein through an arc as shown 130

in the present construction of approximately 90°. Said pistons as shown, are each provided on the inner side or that adjacent to the abutment with a central diametrical 5 cylindrically curved bearing rib 35, as shown in Figure 4, which seats in the concave recess or seat at the apex of its abutment 20, bearing on the packing therein. As shown also, each piston is provided with a peripheral flange 36, on its face opposite the abutment, said flange fitting closely within the cylinder and provided with suitable packing 37 of the usual ring type or any suitable form to afford a pressure proof joint. Integrally connected with the ring or sleeve 15, which fits in the outer end of each cylinder, is a yoke, the arms 38, of which extend inwardly one on each side of the axis of each cylinder, and bear at their ends 20 upon the opposite ends of a pintle or shaft 39, seated in a bearing or recess therefor, in the outer face of each piston, along the diameter thereof, and directly above the bearing of the piston upon the abutment, as shown more fully in Figures 4 and 9. At the inner side of each of said arms, and rigidly bolted or otherwise secured upon the outer face of the piston are cap blocks 40, which fit over the ends of said shaft and 30 are bolted or otherwise secured to the piston, permitting free oscillatory movement of each piston to the required degree on its abutment, but holding the same securely in place thereon.

At the inner end of each of the brackets or fixed crank arms 18, which are integral with the respective shafts 7 and 8, and projecting obliquely into the outer end of each of the cylinders, is journalled a shaft 41, which lies radially in said cylinder and the axis of which lies in a plane with the opposed inclined side of the adjacent abutment for that cylinder when the piston in said cylinder is at one of its extreme positions. Rigidly secured on each of said shafts 41, is a fork 42, which extends at its inner edge along the piston at a diameter and at a right angle with the shaft 39. Seated in a suitable bearing recess on each side of the piston are radially directed shafts 43, over which are secured bearing caps 44. Each of said shafts is provided with a longitudinal groove or seat in its upper side into which extends a tongue or extension 45, from the fork near the ends thereof, as shown in Figure 12, and in dotted lines in Figure 4. Said fork, on each side thereof from said tongues inclines upwardly and outwardly to afford clearance for the movement of the piston. The piston bearings may be readily adjusted for wear by means of the constructions hereinbefore described.

In the construction illustrated, in which the engine is shown in portable form adapted for use in operating tools, such as pneu-

matic tools, the tool holder and thrust shaft are mounted in the engine frame casing parallel the axis of the engine, although of course such parallel relation is not essential. For this purpose, as shown, the casing is extended rearwardly from the inlet side of the engine and provided with bearing sleeves 46 and 47, therein, in the upper frame cap or head and also near the lower end of the intermediate frame casing to receive the thrust shaft therein, and a geared reduction is provided in the gear case whereby the drive of the engine is communicated to the tool holder which projects through and below the lower head of the gear case. A cylindrical thrust block 47^a, is inserted upwardly in the lower bearing sleeve 47, and is provided with a peripheral flange 48, which bears against the lower end of the bearing sleeve, and threaded therein is a screw shaft 49, which, as shown, engages therein with a left thread and when seated in place will be rigidly secured for movement therein in any suitable manner. The upper end of said screw shaft is of considerable length and extends well up toward the upper bearing sleeve 46, and is provided with a right thread, and threaded thereon is a thrust shaft 51, rotatively journalled in said upper bearing sleeve 46, and provided at its upper end with a center 52, adapted to re-act against any suitable clamping or pressure exerting device, such, for example, as the so-called "old man" familiarly known in this art.

On the upper end of said thrust shaft is a hub 53, positioned somewhat below the extremity thereof and provided with radially directed arms 54, whereby the thrust shaft may be rotated.

Engaging against the lower end of the thrust block 47^a, and the flange 48 thereof, is a bearing member 55, forming one member of a ball or other anti-friction bearing and extending upwardly through the bearing sleeve in the gear case is a chuck 56, of a familiar form, which is flanged at its upper end to afford a co-acting bearing surface having a suitable race, and affording the other member of said anti-friction bearing. Said chuck, as shown, is cylindrical and extends through a bushing of suitable bearing metal 57, which is flanged at its upper end to rest upon the inner side of the gear case cap, and at its lower end is shaped, as well as the lower end of the lower hub or bearing sleeve in the gear case cap, to afford a seat for a suitable gland or packing 58, on which pressure is exerted by means of a threaded follower 59, threaded on said hub, and which fits closely around the chuck. A toothed gear 60, is rigidly secured on the chuck above the flange of the bushing 57, to rotate thereon, said gear wheel meshing with suitable pinions 61, disposed on opposite sides

of the gear, and journalled each upon a stud shaft 62, rigidly secured to the gear case cap or partition 2, and extending upwardly in the gear case. Integrally connected with each of said pinions 62, are gear wheels 63, each of which meshes with a pinion 64, rigidly secured to the hub or sleeve 14, of the lower cylinder.

From the construction described, it will be seen that the tool is positively driven through the medium of said train of gears from the engine, and pressure may be exerted upon the tool, or the pressure may be released or reduced by the operation of the thrust shaft which acts substantially as a screw jack for the purpose.

In the reversing construction illustrated in Figures 13 to 16, inclusive, provision is made for reversing the drive of the engine, and varying the cut-off to suit the requirements of the work or to stop the engine. For this purpose as shown, the engine is constructed as before described, with the exception of the throttle and reversing mechanism. For this purpose as shown, the valve casing 65 is provided, of a size to receive the rotative valve block and a shifting valve segment 73. Said valve casing 65, is cylindrical and may be constructed as shown or in two sections formed as illustrated with reference to the valve casing shown in Figure 5, and is provided with a tubular extension 66, having an open port on each side thereof, and secured to the casing frame, as shown in Figure 13. Extending into the casing frame, is a cylindrical rotatable throttle valve 67, which fits closely within the extension 66, of the valve casing, and in its inner end is provided with a V-shaped partition 68 extending from opposite sides thereof one side of said partition is provided with an aperture or port 69, to afford an inlet port for the valve casing. Said V-shaped partition extends inwardly and at its inner end 70, bears against a web 70^a, integral with the valve casing of a width slightly greater than one of the inlet ports, as indicated at 70^a. The end of said throttle valve sleeve extends inwardly to a position to close the port from the sleeve extension 66, of the valve casing, the side thereof adjacent the port inlet 69, through said partition and on its opposite side being provided with a port 71 therethrough, adapted to register with the port in said valve casing.

As shown, a lever 72, is engaged on said throttle valve outside the casing frame, to rotate the throttle when desired, approximately through 180°, thus reversing the ports to enable said engine to rotate in either direction, or at 90° cutting off the inlet and stopping the engine.

Within the valve casing is a shiftable valve cut-off comprising a segment shaped member 73, cored on opposite sides to afford

inlet or exhaust chamber, the periphery of said member being cut away or reduced to permit a partial rotation thereof in the valve casing as shown in Figure 13, an abutment 74, being provided in said valve casing, one 70 on each side thereof, and affording stops to limit the adjustment of the valve cut-off 73, to properly proportion the size of the inlet and exhaust chambers for maximum efficiency in whichever direction the rotation of the engine may be affected, said member being symmetrical and provided on each side with an extension of equal length to engage said abutments at the proper limit of adjustment, the chambers on each side of the valve block communicating into the throttle sleeve on either side of the partition. As shown also, the valve casing 65, is provided with a peripheral slot at the rear side thereof, and secured on the valve cut-off 73, and extending outwardly through said slot is a slotted arm 75, connected with the inner end of the shifting rod 76, the outer end of which extends through the casing frame, and is provided with means for manual engagement. The abutments 74, may be omitted and the adjustment of the valve cut-off limited by the length of the slot in the valve casing as also shown in Figure 13.

The operation is as follows:

Pressure is admitted through the valve casing and valve block and through the abutment, then at inlet position with reference to the valve block, and in which the piston is then inclined to cover the port through the abutment receiving the inlet, as for example, the piston in the lower cylinder shown in Figure 4.

The pressure exerted on said piston acts against the fork 42, extending transversely 105 the shaft of said piston, and which is secured to the bearing shaft on which the engine is journalled, and rotation is produced in said cylinder. When the lower piston above referred to is at inlet position, the 110 other piston is nearing its cut-off position, but the pressure therein is still acting expansively, while, of course, on the opposite side of each of said pistons, the exhaust is taking place, and it will be seen that there 115 is no dead-center position for said engine, as one or both pistons is always receiving a pressure effectively from one or the other of its pressure chambers, and such pressure must continue until the other piston has 120 started its movement from its initial pressure position. As the engine rotates, the forks 42, on each piston, which are rotatably secured on the non-rotative brackets or crank arms 18, also rotate in its bearing the pressure reacting against the same to cause rotation of the engine as the piston oscillates freely from side to side to its extreme limits on its shaft 39, which holds the piston to its seat on the abutment as pressure is alternate- 125 130

ly received on each side of its abutment. The shafts 43, before described, roll slightly in their respective radial seats at opposite edges of the piston, the construction being such as to afford freedom and precision of movement of the pistons with little friction.

When a reversing engine is desired, or the cut-off varied, a construction shown in Figures 13 to 16 inclusive may be utilized, and the throttle valve may be rotated to bring the exhaust port at the inner side of the partition in register with one of the ports through the sleeve extension on the valve casing, and the ports through the said partition into register with one of the valve chambers which in that adjustment serves as the inlet side. The valve cut-off is then adjusted by means of the rod 76, to afford the proper cut-off. In this position, the operation of the engine is as before described, the exhaust, however, passing through the exhaust port into the engine frame casing, and then escaping through the exhaust pipe 28^a, which is shown on the opposite side of the casing from the engine proper and also constitutes an operating handle. If it be desired to stop the engine, the throttle valve may be rotated by means of the lever 72, to close both the inlet and exhaust ports through the sleeve extension of the valve casing, or the engine may be reversed by rotating said throttle to approximately 180° from its former running position, at which time, the inlet port from the throttle valve will communicate with the port on the opposite side of the sleeve extension of the valve casing, while the port through said extension formerly blocked, is now open in register with the exhaust port of the throttle valve, or in other words, the opposite adjustment from that illustrated in Figure 13. Of course where the device is utilized for portable purposes in operating tools, a suitable hose pipe is connected with the inlet, and if desired, the exhaust pipe also, and will permit the tool to be moved about as the work requires.

In the construction illustrated, the pinion 64, which rotates with the engine, drives to the gears 63, both of which are in mesh therewith and journalled in the gear case, and the pinions rigidly secured on said gears, mesh with the gear 60, secured on the chuck 56, to rotate the same, owing to the double geared drive thus afforded or double geared drive stress on bearings and gear teeth is much reduced and wear and breakage and repair avoided, said chuck of course, may be of any preferred kind of construction such as commonly used on pneumatic tools, or any other preferred type.

When the tool is applied to its work, pressure may be exerted by means of the handles 54, radially extending from the upper end of the thrust shaft, or the inlet and exhaust

connections which serve as handles, to press the tool into its work, or to vary the pressure. Conveniently, however, the pressure may be applied to practically any desired extent by means of any of the well known clamping devices, such as the so-called "old man" heretofore used for such purposes, the upper arm of which is engaged by the center point on the upper end of said thrust bar, and the tool pressed to its work by rotation of the thrust bar, by means of said handles.

It is to be observed that all parts of the device are readily and quickly accessible owing to the construction of the casing frame and the simplicity of construction, which permits quick removal of the entire engine and installation of another similar engine. In some instances with larger engines I omit the yoke 38, and secure the ends of the shaft 39, in suitable seats in the cylinder walls passing the ends of the shaft through the piston flange for that purpose. The momentum of the entire mass of the engine is utilized for driving purposes, thus enabling high efficiency to be obtained with relatively light weight, and furthermore that the drive is at all times positive under the pressure applied.

It is to be understood that numerous details of construction may be varied without departing from the principles of this invention, and I therefore do not purpose limiting the patent to be granted, otherwise than necessitated by the prior art.

I claim as my invention:

1. A device of the kind described comprising a plurality of cylinders adapted to rotate about a common axis, a piston rotating with each cylinder and oscillatable therein, and valve mechanisms between adjacent cylinders having portions thereof connected to said cylinders.

2. A device of the kind described comprising a pair of cylinders arranged to rotate about a common axis, a piston in each cylinder rotating therewith and oscillatable therein, a valve block between the cylinders and rigidly connected thereto, and a valve member having ports therein adapted to register with ports in the said block.

3. A device of the kind described comprising a pair of cylinders arranged to rotate about a common axis, a piston in each cylinder rotating therewith and oscillatable therein, a valve block between the cylinders and rigidly connected thereto, a valve member having ports therein adapted to register with ports in the said block, and bearing means for supporting the outer ends of the cylinders.

4. A device of the kind described comprising a rotating cylinder, a piston rotating therewith and oscillatable about a diameter of the cylinder, a member secured to the piston and pivotally movable thereto about an axis substantially perpendicular to said

- 7
- diameter, a shaft secured to said member substantially perpendicularly to said axis, a stationary bearing member for said shaft adapted to hold the latter obliquely with respect to the axis of rotation of the cylinder, and a bearing on said bearing member for supporting the cylinder at the end adjacent said shaft.
5. A device of the kind described comprising a rotating cylinder, valve gear adjacent one end thereof, a stationary shaft projecting through the other end of the cylinder and adapted to support such end, a piston within said cylinder, pivoted connections between the piston and the cylinder and a rotatable member within the cylinder, and a bearing within the cylinder rigidly secured to said shaft for carrying said rotatable member, the axis of rotation of said member in said bearing being obliquely arranged with respect to the axis of rotation of the cylinder.
10. A device of the kind described comprising a rotating cylinder, valve gear adjacent one end thereof, a stationary shaft projecting through the other end of the cylinder and adapted to support such end, a piston within said cylinder, pivoted connections between the piston and the cylinder and a rotatable member within the cylinder, and a bearing within the cylinder rigidly secured to said shaft for carrying said rotatable member, the axis of rotation of said member in said bearing being obliquely arranged with respect to the axis of rotation of the cylinder.
15. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
20. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
25. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
30. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
35. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
40. A device of the kind described comprising a rotating cylinder, a piston movable therein, a valve member secured to and rotating with the cylinder having ports therein, a valve casing having inlet and exhaust connections thereto and ports adapted to register with the first ports, means for reversing the connections between the inlet and exhaust connections and the ports in the casing, and means for simultaneously changing the effective length of the latter ports.
45. A device of the kind described comprising a pair of cylinders adapted to rotate about a common axis, a valve mechanism for connecting the cylinders, and a piston in each cylinder, said piston being oscillatable about axes in substantially perpendicular planes.
50. A device of the kind described comprising a pair of cylinders adapted to rotate about a common axis, a valve block therebetween for admitting fluid to both cylinders, a yieldingly mounted valve casing, and means for rigidly supporting the outer ends of the cylinders.
55. A device of the kind described comprising a pair of cylinders adapted to rotate about a common axis coincident with the centers of the cylinders, a valve mechanism between the cylinders and an oscillatable piston in each of said cylinders, said pistons being oscillatable on axes in perpendicular planes.
60. A device of the kind described comprising a pair of cylinders adapted to rotate about a common axis coincident with the centers of the cylinders, a valve mechanism between the cylinders and an oscillatable piston in each of said cylinders, said pistons being oscillatable on axes in perpendicular planes.
65. A device of the kind described comprising a casing, a pair of cylinders adapted to rotate about a common axis arranged within the casing, means for rigidly supporting the outer ends of the cylinders from the casing, a valve block between the cylinders for admitting fluid to both cylinders, and a valve casing therefor yieldingly supported by the casing.
70. A device of the kind described comprising a pair of cylinders adapted to rotate about a common axis, a valve block therebetween for admitting fluid to both cylinders, and a valve casing for said block, said valve block having fluid passages therein of greater cross section than the area of the ports in the valve block.
75. A device of the kind described comprising a rotating cylinder, a valve block rotating therewith adapted to admit fluid into the cylinder, and a valve member for said block, said valve block having fluid passages therein of greater cross section than the area of the ports in the valve block.
80. A device of the kind described comprising a cylinder, a rotating valve block therefor having ports therein, a valve member having inlet and exhaust connections thereto and ports adapted to register with the first ports, means for reversing the said connections with the second ports, and means for changing the effective length of the second ports to allow proper cut-off and unrestricted exhaust in both positions of said connections.
85. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
90. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
95. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
100. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
105. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
110. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
115. A device of the kind described comprising a cylinder, a rotating valve block therefor having ports therein, a valve casing having inlet and exhaust connections thereto, a fixed abutment on the casing bearing against one side of the block and an arcuate member between the opposite side of the block and the casing adapted to move about the axis of the block to vary the effective length of the ports formed in the casing between the ends of said member and said abutment, means for reversing the inlet and exhaust connections to the ports, and means for moving said arcuate member to allow proper cut-off and unrestricted exhaust in both positions of said connections.
120. A device of the kind described comprising a pair of cylinders arranged to rotate about a common axis, a piston in each cylinder rotating therewith and oscillatable therein, a valve block between the cylinders and rigidly connected thereto having four ports therein substantially 90° apart, and a valve member having ports therein adapted to register with the ports in said block.
125. A device of the kind described comprising a casing, a pair of cylinders therein adapted to rotate about a common axis, bearings for the outer end of the cylinders carried by the casing, a valve block between the cylinders and rigidly connected thereto,

18. A device of the kind described comprising a valve case having ports therein adapted to register with ports in the block, and a yielding connection between the valve case and a fluid supply pipe carried by the casing, the exhaust from the valve case passing into the casing.
19. A device of the kind described comprising a pair of cylinders adapted to rotate about a common axis, a piston in each cylinder rotating therewith and oscillatable therein, a valve block between the cylinders and rigidly connected thereto having four ports therein substantially 90° apart, and a valve member having ports therein adapted to register with the ports in said block, the ports in said valve member being all longer than the distance between adjacent ports in the valve block thereby avoiding dead centers.
20. An engine of the class described comprising a pair of axially aligned cylinders rotatable about their longitudinal axis, each of said cylinders closed at each end, and a piston in each cylinder rotating therewith and oscillatable therein.
21. An engine of the class described comprising a rotatable cylinder, a piston movable therein, a valve member secured to and rotating with the cylinder having ports therein, a second valve member having inlet and exhaust connections thereto and having ports adapted to register with the first ports, and means for changing the effective length of the ports in the second member.
22. An engine of the class described comprising a pair of cylinders aligned with one another and rotatable about their longitudinal axes, a valve block rigidly connected between said cylinders and rotatable therewith, a valve casing therefor, and bearings for rigidly supporting the outer ends of the cylinders for rotation thereof as a unit.
23. An engine of the class described comprising a pair of cylinders aligned with one another and rotatable about their longitudinal axes, and bearings for rigidly supporting the outer ends of the cylinders for rotation thereof as a unit.
24. An engine of the class described comprising a pair of cylinders one at each end and longitudinally aligned, said cylinders rotatable as a unit about their longitudinal axis, valve mechanism interposed between said cylinders controlling the inlet and outlet thereof, and an axial bearing provided for said cylinders at each end thereof.
25. An engine of the class described comprising a casing, a pair of cylinders adapted to rotate about their longitudinal axis arranged within the casing, means for rigidly and rotatably supporting the outer ends of the cylinders in said casing, a valve block 70 between the cylinders for admitting and exhausting fluid to and from said cylinders, and a valve casing therefor supported by the casing.
26. An engine of the class described comprising rigidly associated cylinders rotatable about a common longitudinal axis, each of said cylinders closed at each end and having a piston movable therein, and a valve block 75 affording rigid connection between said cylinders and controlling the inlet and outlet thereto, said valve block having passages therein, and a valve casing in which said valve block is rotatably mounted, said casing having passages for registration with said 80 passages in said valve block with those passages for co-action with the passages in the valve blocks, elongated to increase the area thereof.
27. In an engine of the class described a 90 rotative cylinder rotative about its longitudinal axis, a valve block for said cylinder, a valve member therefor not rotatable therewith having passages therethrough to register with passages in the valve block, a yieldable fluid inlet connection on said valve member, a surface thereof subject to the pressure of the fluid tending to hold the valve member sealing on the valve block and of greater area than the component lift 95 area of the valve member passages tending to lift the member from the block.
28. An engine of the class described comprising a rotative cylinder, a valve block rotatable therewith and having ports therein, a valve casing having inlet and exhaust connections thereto and ports adapted to register with said ports in said valve block, and means for changing the effective length of the intake ports.
29. An engine of the class described comprising a rotative cylinder, a valve block rigidly associated therewith having ports therein, a valve casing having inlet and exhaust connections thereto in which said 110 valve block is adapted to rotate, a fixed abutment on the casing bearing against one side of the block, and a curved member between the opposite sides of the block and the casing adapted to move about the axis 115 of the block to vary the effective length of the ports formed in the casing between the end of said member and said abutment.
30. An engine of the class described comprising a rotative cylinder, a valve block 120 rigidly associated therewith having ports therein, a valve member having inlet and exhaust connections thereto relative to which said valve block is adapted to rotate, a fixed abutment on the member bearing 125
- 130

- against one side of the block, a movable means between the opposite side of the block and the member adapted to move about the axis of the block to vary the effective length 5 of the ports in the member between the end of said movable means and said abutment, and means for moving said means to allow proper cutoff and unrestricted exhaust in both positions of said connections.
- 10 31. An engine of the class described comprising a pair of cylinders longitudinally aligned and adapted to rotate about a common longitudinal axis, a piston in each cylinder rotating therewith and oscillatable 15 therein, a valve block between the cylinders and rigidly connected thereto, a pair of ports for each cylinder in said valve block, said ports of a pair substantially 180 degrees apart, and a valve casing having ports 20 therein adapted to register with the ports in said block during rotation thereof.
32. An engine of the class described comprising a rotatable cylinder adapted to rotate about its longitudinal axis, a piston 25 movable therein, and a valve block associated with said cylinder for rotation therewith and having ports therein controlling the inlet and outlet from said cylinder, with said ports disposed substantially 180 degrees apart, and a relatively stationary 30 valve member having ports therein adapted to register with the ports in said block at predetermined intervals during rotation thereof.
- 35 33. In an engine of the class described a valve block, a valve casing therefor, ports in said casing and block adapted to register with one another during rotation of the valve block in the casing, and a yieldable connection to said valve casing of greater 40 area than the area of the ports therein whereby the valve casing is held tightly against the valve block by the pressure of the fluid being admitted.
34. In an engine of the class described 45 comprising a frame, a revolving engine, a valve block with ports therein revolving with said engine, a stationary valve member with ports adapted to register with ports in the valve block, yieldable connections between the stationary valve members and the frame so arranged that the fluid pressure keeps the valve balanced and seated.
35. In an engine of the class described a 50 rotating cylinder, a piston rotating therewith, and oscillating about a transverse diameter of the cylinder substantially balanced on its axis of oscillation.
36. In an engine of the class described a 55 cylinder rotative about its longitudinal axis, a valve block having passages therethrough communicating into said cylinder, and said passages of varying diameter increasing in size toward the point of communication with the cylinder.
